UNITED STATES PATENT OFFICE.

ALVIN TRESSELT, OF NEW YORK, N. Y.

TIME-SWITCH.

No. 858,040.

Specification of Letters Patent.

Patented June 25, 1907.

Application filed January 23, 1907. Serial No. 353,579.

To all whom it may concern:

Be it known that I, ALVIN TRESSELT, a citizen of the United States, residing in the city of New York, borough of Brooklyn, in the county of Kings and State of New York, have invented a certain new and useful Improvement in Time-Switches, of which the following is a specification.

The invention relates to time-controlled automatic electric switches, and the object of the invention is to provide efficient mechanism for operating the switch, and a time mechanism which will accurately control such operating-mechanism; the whole being simple in construction and operation, and arranged to permit either mechanism, and also the switch, to be easily removed for inspection or repairs without affecting the others.

The invention consists in certain novel features of construction and arrangement whereby the above objects are attained, to be hereinafter described.

The accompanying drawings form a part of this specification and show a preferred form of the invention.

Figure 1 is a face view of the mechanism, the inclosing case being shown in section. Fig. 2 is a corresponding side view. Fig. 3 is an elevation of a portion of the switch-operating mechanism on a larger scale, and Fig. 4 is a plan view showing another portion of the same mechanism.

Similar letters of reference indicate the same parts in all the figures.

A is a casing inclosing the switch and other mechanisms, and for the purposes of this description may be understood to be a rectangular box of cast iron having a cover A¹ which may be sealed when closed by a rubber gasket as usual.

The casing is preferably long and narrow as shown, to be received easily within an electric-light post or other limited space. It contains a time mechanism, a switch-operating mechanism, and a switch. The time mechanism B comprises a revolving dial B¹ divided into twenty four spaces each subdivided into four, thus marking the hours and quarters; and bears two sets of numerals from 11 to 12 placed opposite the main divisions. The time-mechanism may be understood to be similar to that of any ordinary or approved type of eight-day, spring clock movement, but having the hour-train B² arranged to revolve the dial B¹ once in twenty-four hours. On the dial sleeve B³ is mounted

two cams B⁴ B⁵ revolving with the dial and held adjustably in place thereon by a spring washer B⁶ and nut B⁷. The ends of the cams reach nearly to the divisions on the dial so that they may be easily set to the times indicated thereby at which the switch is to be turned to the "on" and "off" conditions. A pointer B⁸ overhanging the edge of the dial and attached to the frame of the clock mechanism enables the current time to be read and compared with a standard in the hands of an inspector.

The switch-operating mechanism is marked C and comprises a barrel C¹ the wheel C² of which is in mesh with a pinion C³ on a shaft C⁴ extending through the upper plate of the frame and carrying an arm N. C⁵ is a wheel loosely mounted on the shaft C⁴ but compelled to turn in one direction therewith by the engagement of a ratchet-wheel C⁶ thereon, by a pawl C⁷ carried on the wheel. From the wheel C⁵ extends a train to a fly C⁸ serving to slow the movement of the arm N.

A standard C⁹ on the upper or outer plate serves as a fulcrum for a lever M extending approximately to a line at the transverse diameter of the dial and terminating in a finger M¹ lying in the path of the cams. The opposite end of the lever has two branches M² M³ resembling the pallets of the well-known escapement anchor. The branch M² lies in the path of the arm N and holds it until the finger M¹ has been forced outwardly far enough to release it; the same movement places the branch M³ in the path and again arrests and holds it until the finger M¹ passes the outer end of the cam and again moves inwardly. Thus freed the arm N completes its revolution and is again stopped by the branch M². The short movement of the arm between the branches M² M³ is ineffective except in preparing for the long sweep from the branch M³ to the branch M².

D is the switch, shown as a "Perkins 4-pole," comprising a porcelain or other non-conducting base secured to the casing A, and a cover D¹ inclosing the fixed and moving contacts. It is of the spring type in which by the rotation of a central shaft D² a spring D³, not fully shown, is partially wound and released, the tension thus created serving to throw the switch instantaneously to the "on" or "off" condition as indicated by the appearance of such word in a window d in the cover D¹.

On the shaft D² I mount a gear-wheel D⁴

in mesh with the barrel-wheel C^2 of the switch-operating mechanism, and so proportioned relatively to the latter that one complete circuit of the arm N will induce a 5 partial revolution of the shaft D^2 sufficient to throw the switch. One full revolution of the wheel D^4 induces four changes of the switch, and the condition of the latter may be seen through one or the other of the openings d^1 in such wheel as it is presented in coincidence with the window d , the gearing being so proportioned as to induce such coincidence when the arm N is arrested by the branch M^2 . The upper end of the shaft or 15 switch-stem D^2 is supported by a V-shaped brace D^5 removably secured to the outer plate of the switch-operating mechanism C .

In the branch M^2 of the lever M is a notch m receiving a fixed stud C^{10} serving to reinforce the standard C^9 by taking a portion of the strain caused by the action of the arm N , and especially in resisting the force of the blow delivered by the arm at the completion of its revolution. The end of the arm N and 20 the outer face of the branch M^2 with which it contacts are curved on a segmental line of which the standard C^9 is the center, so that the friction due to pressure is practically constant for all positions of the lever M , and 25 therefore the effect of the latter upon the clock movement is nearly uniform.

M^4 is a light helical spring coiled about the standard C^9 and exerting its tension in the direction to force the lever M toward the 30 center of the dial and insure the inward movement when the finger M^1 passes the point of either cam. Both cams are alike, one serving to turn the switch to the "on" 35 position and the other to the "off"; by setting them to the desired times as indicated by the dial the changes will be made automatically.

The driving-spring in the barrel C^1 is of sufficient strength to overcome the switch-spring D^8 at each throw. The effect is to cushion the blow delivered to the branch M^2 by the arm N . In making its revolution the arm passes the short distance between the branches idly and on leaving the branch 40 M^2 starts with the full force of the barrel-spring resisted by the fly-train and by the gradually increasing opposition of the switch-spring until the release-point of the latter is reached, which occurs just prior to contact of the arm and branch M^2 ; thus it will be 45 seen that the arm travels with full force only through a short arc and is arrested before any considerable momentum is acquired. The ratchet-wheel C^6 and pawl C^7 in the fly-train permits such train to continue 50 to run after the arm has been arrested, thus avoiding shock to the mechanism due to sudden stoppage.

In the apparatus as here described the 55 spring in the barrel C^1 is strong enough to

throw the switch sixteen times, which is assumed to be requisite for the eight days run of the clock movement,—that is one "on" and one "off" movement in each twenty-four hours, for controlling an electrically 70 illuminated sign or the like.

To remove the time mechanism it is only necessary to release and lift off the lever M and remove the screws holding the movement to the case. The switch-operating 75 mechanism may be removed by simply taking out the holding screws, and the switch may be removed or inspected by taking away the brace D^5 and removing the gear-wheel D^4 , thus exposing the cover D^1 and 80 permitting the switch to be detached in the usual manner. It will be noted that either of these operations may be performed without disarranging the other mechanisms.

I claim.

1. In a time-switch, a time-movement, a switch, and a switch-operating mechanism, each independent of the others and each removable independently of the other, a cam moved by said time-movement, a lever in the 90 path of said cam, connections from said switch-operating mechanism to said switch for actuating the latter, an arm revolved by said switch-operating mechanism, and branches on said lever arranged in the path 95 of said arm and constructed to arrest and release said arm and means operative after the movement of said arm has ceased and constructed to retard the movement of said arm.

2. In a time-switch, a switch-operating 100 mechanism, an arm revolved thereby, means for arresting and releasing said arm, a fly-train operatively connected with said arm for retarding the movement of said arm, means permitting said arm to travel with 105 full force through a short arc only and a ratchet-wheel and pawl in said fly-train constructed to permit said fly-train to run by momentum after said arm has stopped.

3. In a time-switch, a switch having a 110 spring, and a switch-operating mechanism controlled by the movement of an arm thereon in opposition to said spring, and means for tempering the force of said arm and means for arresting said arm after the release of said spring and the movement of 115 said switch and permitting said arm to travel with full force through a short arc only.

4. In a time-switch, a time-movement, a 120 switch, and a switch-operating mechanism, each independent of the others and each removable independently of the other, a dial revolved by said time-movement, cams revolving with said dial and adjustable relatively thereto, a lever having a finger in the path of said cams, branches on said lever, an arm revolved by said switch-operating mechanism and arrested and released by said 125 branches, means permitting said arm to 130

travel with full force through a short arc only and connections from said switch-operating mechanism to said switch for actuating the latter.

5. In a time-switch, a time movement, a switch and an interposed switch-operating mechanism, an arm operated by said switch-operating mechanism, means operative after the movement of said arm has ceased and
10 constructed to retard the movement of said arm, cams on the dial of the time movement,

an oscillating lever interposed between said cams and arm, and means serving to cushion the contact between said arm and the coacting portions of said lever.

In testimony that I claim the invention above set forth I affix my signature, in presence of two witnesses.

ALVIN TRESSELT.
